UNITED STATES PATENT OFFICE.

FREDERICK WILLIAM MAGEE, OF LONDON, ONTARIO, CANADA, ASSIGNOR OF ONE-HALF TO THOMAS WILLIAM BAKER, OF LONDON, ONTARIO, CANADA.

HOT-WATER HEATER.

1,328,682.

Specification of Letters Patent. Patented Jan. 20, 1920.

Application filed March 30, 1918. Serial No. 225,793.

To all whom it may concern:

Be it known that I, FREDERICK WILLIAM MAGEE, of the city of London, in the county of Middlesex, in the Province of Ontario, Canada, have invented certain new and useful Improvements in Hot-Water Heaters, of which the following is the specification.

My invention relates to improvements in hot water heaters and the object of the invention is to provide an inexpensive, durable and efficient heater which may be readily installed with a minimum amount of labor at any height desired and with a minimum amount of injury to the house structure, in which leakage of the condensing moisture through the joints of the gas discharge pipe is prevented and the consequent rusting of such pipe and also preventing dirtying of the water within the heater due to the condensations carrying rust and other foreign matter back into the heater from the discharge pipe, in which means are provided for preventing the gas becoming surcharged with moisture thus decreasing its efficiency immediately it leaves the burner, in which the water is finely divided and distributed in film like form over the heated surfaces and dry gas brought into contact therewith, in which the equal distribution of water feed through the head is unaffected by the heater not being set vertical, in which the accumulation of gas within the heater is avoided and the consequent explosion thereof, in which there is a free outlet for expansion of exploding gases, in which there is a free circulation of the generated heat, in which there are no exterior heated parts liable to injure woodwork or any person coming in contact therewith, in which the water discharge may be adjusted annularly so as to extend from any position from the bottom of the heater and in which excessive draft is avoided liable to suck out the pilot light and it consists essentially of the following arrangement and construction of parts as hereinafter more particularly explained.

Figure 1 is a general perspective view of my heater.

Fig. 2, is a vertical section.

Fig. 3, is an enlarged perspective detail of the head of the heater on which the condensing apparatus is supported.

Fig. 4, is a perspective detail of the conical deflecting plate.

Fig. 5, is a perspective detail of the central pan supported beneath the central orifice of the deflecting plate shown in Fig. 4.

Fig. 6, is an annular pan on which the pan shown in Fig. 5 is centrally supported and from which the water discharge pipe extends.

In the drawings like letters of reference indicate corresponding parts in the various figures.

1 indicates the gas inlet pipe by which the main weight of the heater is carried. The lower end of the pipe 1 is connected to a suitable floor bracket or elbow 2 through which the pipe 1 is connected to the supply pipe. 3 indicates a wall bracket provided with a bracket portion 3^x having a right angular orifice 3' into the lower arm of which the lower end of the pipe 1 is secured. 4 indicates the water inlet pipe which is connected at its upper end by an elbow 4^x to a forwardly extending pipe 4'. 4² indicates an elbow, to one horizontal arm of which the opposite end of the pipe 4' is secured. The elbow 4² is provided with an upwardly extending arm 4³ connected by a pipe 4⁴ to a valve casing 4⁵ in which is located a valve controlled by a stem 5. 4⁶ indicates a pipe leading rearwardly from the valve casing 4⁵ and connected by an elbow 4⁷ and union joint 4⁸ to a vertical pipe 4⁹.

1^x indicates a pipe leading forwardly from the bracket 3^x, one end of such pipe being secured in the other arm of the right angular orifice 3' hereinbefore described. 6 indicates a valve casing provided with a valve controlled by a valve stem 6^x. 1² indicates a tie bar connecting the pipes 1^x and 4' together. 6' indicates an elbow connected to the valve casing 6, one horizontal arm of which is secured to the outer end of the pipe 1^x, the other horizontal arm being connected by a screw plug 6² to the opposing horizontal arm of the elbow 4². By this means the pipes 1^x and 4' and valve supported thereby are secured and tied positively together so as to form a rigid structure and which are kept absolutely in a definite relative position one to the other.

The valve stems 6^x and 5 are controlled by hand levers 7 and 8 provided with adjustable mechanism 9 and 10 for controlling the water and gas supply which I will not describe in detail as it forms the subject matter of a separate and copending applica-

tion, other than to say that the apparatus 10 comprises a disk 10^x having an arc-shaped cut out portion 10' and the apparatus 9 comprises a complete disk 9^x carried by the 5 stem 5 having a lever extension 9' having an arc-shaped head engaging the arc-shaped recess 10' thereby rendering it impossible to swing the lever 7 controlling the gas supply without first swinging the lever 8 controlling 10 the water supply whereby it is insured that the water is first admitted to the heater before the gas supply is turned on.

6³ indicates a pipe extending upwardly from the valve casing 6. 12 indicates the 15 gas burners which are supplied with gas from the pipe 6³. 13 indicates a supporting spider provided with a central hub 13^x which is secured to the pipe 6³ and an annular outer rim 13'.

20 14 indicates an intermediate cylindrical casing, which is suitably secured at its lower end to the rim 13'. 15 indicates the upper head of the heater, which fits within the upper end of the intermediate casing 14. 25 The casing 14 is provided intermediately of its height with a bead 14^x. 15^x indicates an annular flange extending downwardly from the head 15 in proximity to its outer periphery.

30 16 indicates an annular pan, which fits within the casing 14 and rests at its outer edge upon the bead 14^x, the outer wall 16^x of the pan 16 fitting against the interior face of the wall of the casing 14. The inner wall 35 is formed by an annular flange 16' extending upwardly around the central orifice 16². 16³ indicates a water discharge pipe extending downwardly from the pan 16 and through openings between the arms of the 40 spider member 13.

It will be understood that the pan 16 fits freely within the casing 14 so that it can be turned circumferentially to any position desired when the apparatus is being set 45 up so that the position of the pipe 16³ may be adjusted to suit the requirement of the particular location in which the heater is set up.

50 17 indicates a central pan, which is supported upon tubular legs 17^x, which rest upon the bottom of the annular pan 16 around the exterior of the inner wall or flange 16'. The upper ends of the tubular legs 17^x project upwardly into the pan 17 55 at 17' thereby providing that there is always a film of water over the surface of the pan. The tubular legs 17^x are cut off at an incline at 17² whereby the flow of water passing down such tubular legs is 60 directed radially outward therefrom.

I will now describe the head 15 in detail as shown particularly in Fig. 3.

The head 15 is provided with an annular outer flange or wall 15' and a central stem 65 15². 15³ indicates a series of orifices formed

in the bottom of the head 15 and in which are secured a series of tubes 15⁴, the tubes projecting upwardly into the head, the upper ends being below the level of the wall 15', and downwardly from the bottom face 70 of the head as clearly shown in Figs. 2 and 3. The upper end of each tube 15⁴ projecting above the bottom of the pan is provided with a perforation or perforations 15⁵ in proximity to the bottom of the head. All 75 the perforations are equal or of less capacity than the inlet 4¹⁰. It will thus be seen that if the heater is not set quite vertical that the water fed into the head will rise around the upper ends of the tube until all the perforations are beneath the water level. Any overflow passes through the upper ends of the tubes. 15⁶ indicates a circular deflecting plate secured to and carried by the stem 15².

80 18 indicates an inner casing, which fits at its upper end around the exterior of the depending flange 15^x of the head 15. The lower end of the casing 18 fits within the annular outer wall or flange 16^x of the pan 90 16 thereby providing an intermediate dead air space between the casing 18 and the intermediate casing 14. Intermediately of its height and above the level of the central pan 17 the casing 18 is provided with an annular internal bead 18^x.

95 19 indicates a conical deflecting plate, the sides of which slope gradually from the central orifice 19^x, the extreme outer edge of the plate being provided with edge notches 19¹. The deflecting plate 19 rests upon the annular bead 18^x.

100 20 indicates a condenser which comprises an outer cylindrical casing 21 which fits within the annular flange 15' of the head 15, 105 the lower edge of the casing resting upon the bottom of the head. 22 indicates an annular bead formed in the cylinder 21. 22^x indicates a horizontal circular partition, which fits within the casing 20' and rests 110 upon the annular bead 22. The partition 22^x is provided with a central orifice 22¹ provided with a surrounding upwardly extending flange 22². 22³ indicates a chimney, which fits around the flange 22² and extends 115 upwardly therefrom and forms a discharge for waste gases.

120 22⁴ indicates a cover for the casing 21, such cover being provided with a central orifice 22⁵ through which the chimney 22³ extends. The partition 22^x is provided with a series of orifices 22⁶. 22⁷ indicate nipples depending through such orifices, the majority of the nipples preferably extending slightly upward above the upper face 125 of the partition 22^x. One or two of them, however, are made substantially flush with such upper face so as to permit of the complete draining of the water from above the partition when the water supply is cut off. 130

The lower ends of the nipples 22⁷ are preferably provided with inwardly turned elbow portions 22⁸.

24 indicates an outer casing, which is supported by brackets 24^x upon the upper edge of the intermediate casing 14. The casing 24 depends downwardly free of the outer face of the wall of the intermediate casing 14 thereby providing for an air space allowing for free circulation of cool air upwardly between the outer and intermediate casings and thereby keeping the outer casing cool so as to protect surrounding woodwork or any person coming in contact therewith from being burned.

25 indicates a branch pipe, which extends from the main gas supply pipe and is provided with an elbow 26 from which extends a pipe 27, the upper end of which extends into close proximity to the heads of the burners 12. It will be seen that the pipe 25 supplying the pipe 27 extends from the gas supply pipe at a point before the gas supply reaches the controlling valve 6 and, therefore, a constant supply of gas is supplied to the pipe 27. As will be seen from the drawing this pipe is a very small pipe and is provided with a suitable controlling valve at 27^x so as to just supply sufficient gas to form a small pilot light, which is constantly kept lighted.

Beneath the valve 27^x a pipe 28 is branched off from the pipe 27. 29 indicates an orifice, which extends through the outer and intermediate casings 24 and 14 respectively. The pipe 28 is provided with an upward extension 30 provided with a controlling valve 31 and terminating in a pilot burner 32, which is designed to be lighted by the operator. The burner 32, when lighted, projects a flame radially into the heater thereby serving to light the burners 12. The inner pilot formed by the pipe 27 as has been before stated is kept constantly lighted and serves to burn up any gases which tend to accumulate within the heater and which, if allowed to accumulate, would provide an explosive mixture which would violently explode when the outer pilot light 32 is lighted. By providing the inner pilot this is obviated.

It is not always necessary to light the outer pilot, the burners being lighted from the inner pilot immediately the gas is turned on but if the inner pilot should go out or it is found necessary the outer pilot could be lighted so as to light the burners and at the same time re-light the inner pilot.

4¹⁰ indicates the water inlet to the condensing casing 20. 4¹¹ indicates an elbow connection between the upper end of the pipe 4⁹ and the inlet 4¹⁰.

When it is desired to heat the water the lever 8 is swung down thereby carrying the

arc-shaped extension 9' thereof upward clear of the arc-shaped recess 10' of the disk 10^x and thereby freeing the lever 7 operating the gas supply valve. The lever 7 is then sprung upward so as to admit a supply of gas which passes up through the pipe 1, through the pipe 1^x, valve 6, to the pipe 6³ and upwardly into the burner, the burner being lighted by means of the pilot light supplied by the pipe 27 hereinbefore described. Water passes upwardly through the pipe 4 and through the valve 4⁵, pipe 4⁶ pipe 4⁹ and inlet 4¹⁰ into the top portion of the condenser 20 flowing over the outer surface of the partition 22^x. The water so supplied flows down the nipples 22⁷ into the lower portion of the condenser. As has been before described the majority of the nipples 22⁷ extend upward above the upper surface of the partition 22^x and as the capacity of the nipples which are flush with the upper surface of the partition 22^x is slightly less than the capacity of the supply pipe 4⁹ a thin film of cool water is constantly kept within the upper portion of the condenser covering the upper face of the partition or plate 22^x thereby forming a cooling surface against which hot gases are protected as hereinafter described.

The water passes down through the nipples 22⁷ and is received upon the upper face of the head 15 and flows around the upwardly projecting ends of the pipes 15⁴. Water so supplied passes through the perforations 15⁵ into the interior of the tubes 100 and trickles down such tubes into the interior of the casing 18. The tubes, which are in proximity to the inner periphery of the casing, are located above the conical deflecting plate 19 and, therefore, the water passing through the perforations 15⁵ of such tubes is received by such deflecting plate and is deflected radially outward against the interior face of the casing 18 and then passes down through the notches 19' and continues to flow down the inner face of the casing 18 into the annular pan 16, which supplies the water discharge pipe 16³. The water which passes down the perforations 15⁵ of the central tube 15⁴ passes through the central orifice 19^x of the deflecting plate 19 and is received by the central pan 17.

As has been before described the tubular legs 17^x project upwardly above the bottom of the pan 17 and thereby provide a constant film of water on the top of the pan, the overflow of which passes down through the tubular legs 17^x into the annular pan 16 and from thence with the rest of the water to the discharge pipe 16³. The hot gases from the burners 12 pass upward through the central orifice 16² striking the bottom of the central pan 17 serving to heat the water thereon and being deflected outwardly therefrom and passing upwardly

around the pan through the central orifice 19^x of the deflecting plate 19. From thence it spreads radially upwardly and passes upwardly through the tubes 15⁴ into the condenser, the hot gases passing through the outer tubes passing directly upward into contact with the cooling surface formed by the partition 22^x, and the hot gases passing through the central tubes being deflected by 10 the deflecting plate 15⁶ and deflected outwardly against the lower face of the plate 22^x. By this means any moisture which is contained in the gas is condensed therefrom, the condensations passing down into 15 the water contained above the level of the head 15.

It will, of course, be understood that the level of the water in the head is always above the level of the lower ends or mouths 20 of the elbows 22⁸ thereby preventing hot gases passing therethrough.

After moisture is condensed from the waste gases they pass upward through the stack or chimney 22². By this construction 25 it will be seen that the water flow is divided so that a portion of it is deflected outwardly from the center so as to pass vertically in thin streams down within the interior of the heater over the heated wall surface, the 30 small portion constituting the remainder passing directly down through the center on to the pan 17 forming a thin film thereon. The pan forms another heated surface over which the water is fed, such water 35 passing down through the legs 17^x into the pan 16 thereby allowing the hot gas to pass upward out of contact with the heater and in a dry state into the main portion of the heater so as to maintain there a maximum 40 efficiency. By this means the water flow is broken up and the hot gases passing upward pass between such inner and outer flows and thereby come into intimate contact therewith to raise the temperature 45 thereof, the gases first striking the lower face of the central pan 17 passing upwardly between the inner and outer flows, then through the central orifice of the deflecting plate 19 and then against the lower face 50 of the head 15 so as to raise the temperature of the water carried thereby and through the tubes 15⁴ which are also in contact with such water and through which such water trickles, the discharged gases 55 passing through the head being condensed as above described and passing outwardly through the chimney 22². By this means it will be seen that the temperature of the water may be very quickly raised to any 60 temperature desired within any necessary limit, such temperature being controlled by the rate of flow of the water through the heater, such flow being controlled by any suitable means.

65 By means of the tubes 15⁴ in the head 15

the outlet of draft is distributed thereby preventing the sucking out of the inner pilot light due to direct suction to the chimney.

Such a heater as I have described also 70 may be very quickly installed with a minimum amount of labor, the whole weight of the heater being carried by the gas supply pipe connected with the floor and, therefore, the height of the heater may be very readily 75 adjusted, when such heater is being installed for in order to do this all that it is necessary to do is to cut the gas supply pipe to the required length.

In such a heater as I have described also 80 any danger of the accumulation of gases and consequent dangerous explosion is avoided, in which there is a free outlet for the expansion of gases due to back fire explosion when lighting the burners. Also in 85 this form of heater there are no exterior heated parts liable to be injurious.

I have also provided in this form of heater simple means whereby the water discharge pipe may be adjusted annularly to 90 any position desired to suit the location in which the heater is placed and mainly I have provided means whereby the water flow is broken up to a maximum extent so as to be brought into intimate contact with 95 the hot gases which pass up through the heater thereby enabling the water to be raised very quickly to the desired temperature and to a higher temperature than has hitherto been found possible so far as I am 100 aware.

Also by providing a condensing apparatus between the head of the heater and the chimney outlet I prevent the condensations forming in the chimney which creates 105 rust which is carried back into the heater discoloring the water, such condensations leaking also through the joints of the chimney pipe outlet staining the exterior thereof and dropping on to the floor. Owing to 110 this detrimental effect it has been impractical to raise water to a comparatively high temperature producing steam. By my apparatus I am enabled to raise the temperature to any desired degree and yet obviate 115 this defect.

What I claim as my invention is.

1. In an instantaneous heater, the combination with the cylindrical casing and the water supply pipe, of means at the upper end of the casing for breaking up and distributing the flow into fine streams of falling water, an annular conical member fitting the casing and having peripheral notches and forming an outer annular receiving means and designed to receive the outermost streams of water so as to direct them against the inner face of the casing wall, separate means spaced from the conical member adapted to receive the central 130

streams, a gas burner at the lower end of the heater, and means for distributing the hot gases against the lower face of the central water receiving means to pass upward 5 between the central and outer receiving means and through the water distributing means to a suitable outlet.

2. An instantaneous heater comprising a cylindrical casing, a dished head at the upper end of the casing into which the water supply is discharged, a multiplicity of nipple tubes carried by and arranged evenly throughout the whole surface of the head and passing through the bottom of the 10 dished head and projecting above and below such surface and having perforations in the upwardly projecting portion in proximity to the head.

3. An instantaneous heater comprising a cylindrical casing, a dished head at the upper end of the casing into which the water supply is discharged, a series of tubes passing through the bottom of the dished head and projecting above and below and having 15 perforations in the upwardly projecting portion in proximity to the head, means for receiving the water passing through the perforations and through the tubes, a discharge pipe leading from such receiving 20 means, a gas supply pipe, a burner located at the lower end of the heater and adapted to provide a circulation of heat upward through the tubes of the head, and means interposed between the tubes of the head 25 and the water receiving means for deflecting the water flow so that a portion is carried into contact with the wall of the casing to pass downwardly thereagainst and a portion 30 to pass centrally to the water receiving 35 means.

4. An instantaneous heater comprising a cylindrical casing, a dished head at the upper end of the casing into which the water supply is discharged, a series of tubes passing 40 through the bottom of the dished head and projecting above and below and having perforations in the upwardly projecting portion in proximity to the head, means for receiving water passing through the perforations and through the tubes, a discharge 45 pipe leading from such receiving means, a gas supply pipe, a burner located at the lower end of the heater and adapted to provide a circulation of heat upward through the tubes of the head, a conical plate having 50 a central orifice, and peripheral edge notches located within the casing intermediately between the tubes of the head and the water receiving means.

5. An instantaneous heater comprising a cylindrical casing, a dished head at the upper end of the casing having orifices, vertical tubes secured within such orifices so as 55 to project above and below the head and having perforations in the upwardly projecting 60 portion in proximity to the head.

jecting portions thereof in proximity to the head, an annular water receiving pan located below the head, a conical deflecting plate having a central orifice and peripheral notches located between the head and 70 the receiving pan, and a central pan located beneath the orifice of the conical deflecting plate and the central orifice of the annular receiving pan.

6. An instantaneous heater comprising a cylindrical casing, a dished head at the upper end of the casing having orifices, vertical tubes secured within such orifices so as to project above and below the head and having perforations in the upwardly projecting 75 portions thereof in proximity to the head, an annular water receiving pan located below the head, a conical deflecting plate having a central orifice and peripheral notches located between the head and 80 the receiving pan, a central pan located beneath the orifice of the conical deflecting plate and the central orifice of the annular receiving pan, and tubular legs supporting such central pan within the annular pan. 90

7. An instantaneous heater comprising a cylindrical casing, a dished head at the upper end of the casing having orifices, vertical tubes secured within such orifices so as to project above and below the head and 95 having perforations in the upwardly projecting portions thereof in proximity to the head, an annular water receiving pan located below the head, a conical deflecting plate having a central orifice and peripheral 100 notches located between the head and the receiving pan, a central pan located beneath the orifice of the conical deflecting plate and the central orifice of the annular receiving pan, and tubular legs having their 105 lower ends cut off at an incline supporting such central pan within the annular pan.

8. An instantaneous heater comprising a cylindrical casing, a dished head at the upper end of the casing having orifices, vertical tubes secured within such orifices so as to project above and below the head and having perforations in the upwardly projecting 110 portions thereof in proximity to the head, an annular water receiving pan located below the head, a conical deflecting plate having a central orifice and peripheral notches located between the head and the receiving pan, a central pan located beneath the orifice of the conical deflecting 115 plate and the central orifice of the annular receiving pan, and tubular legs having their upper ends projecting upwardly into the pan.

9. An instantaneous heater comprising an 120 outer cylindrical casing having an open lower end, a dished head at the upper end adapted to receive the water supply, an annular water receiving pan supported in the cylindrical casing intermediately of its 130

height, an inner cylinder extending between the head and the pan and spaced apart from the outer cylindrical casing, a water discharge pipe leading from the annular pan, 5 a burner located in the open lower end of the casing, and a gas supply pipe therefor.

10. An instantaneous heater comprising an outer cylindrical casing having an open lower end, a dished head at the upper end 10 adapted to receive the water supply, an annular receiving pan supported in the cylindrical casing intermediately of its height, an inner cylinder extending between the head and the pan and spaced apart from 15 the outer cylindrical casing, a water discharge pipe leading from the annular pan, a burner located in the open lower end of the casing, a gas supply pipe therefor, an outer casing supported freely upon the 20 aforesaid casing and spaced therefrom and forming an annular air duct extending upwardly around the casing of the heater.

11. In an instantaneous heater, the combination with the casing and means for 25 supplying water to and discharging the gas from the heater, of means for forming such water supply into fine falling streams distributed over the area of the casing, means for directing the outermost streams against 30 the casing wall, annular water receiving means fitting the casing located below the directing means, a central water receiving means spaced between the directing means and the annular water receiving means and 35 designed to receive the water directly from the distributing means to form it into a film and feed the water so formed into the annular water receiving means, and a gas burner located below the annular water receiving means whereby the gas passes upward 40 between the central and annular water receiving means and then between the central receiving means and the casing, then between the central receiving means 45 and the water directing means to the gas discharge.

12. In an instantaneous heater, the combination with the casing and means for

supplying water to and discharging it from the heater, of means for forming such supply into fine falling streams of water distributed over the area of the casing, means for directing the outermost streams against the inner face of the wall of the casing, annular water receiving means located beneath the directing means and fitting the casing, a dished receptacle provided with tubular legs extending through the bottom of the receptacle and protruding from above and resting at their lower ends upon 50 the annular water receiving means, such lower ends being so formed as to allow of the free outlet of water therefrom, a gas burner located below the water receiving means whereby the gases pass upwardly 55 against the lower face of the central water receiving means, around the same and through the center of the water directing means to the exhaust.

13. In an instantaneous heater, the combination with the heater casing, a head therefor having a common passage for the discharge of gas, an inlet for water to the heater and the gas discharge chimney, of a condenser having an annular surface 70 extending around the chimney opening, and a disk located beneath such opening and spaced therefrom to deflect the central portion of the gas flow against the condensing surface to pass therefrom to the chimney 75 opening.

14. In an instantaneous heater, a cylindrical casing, a head for the upper end of the casing having a multiplicity of water inlets distributed therein, a conical plate 80 having a center orifice and peripheral edge notches supported within the casing, a pan located beneath the central orifice, a tubular support for the pan and a water receiver adapted to receive the water passing from 85 the notches of the conical plate and through the tubular legs.
